UNITED STATES PATENT OFFICE.

HAROLD JAMES ARNOLD, OF STIRCHLEY, ENGLAND.

SPRING-HINGE FOR USE WITH SWING-DOORS OR THE LIKE.

1,334,982.

Specification of Letters Patent. Patented Mar. 30, 1920.

Application filed November 22, 1919. Serial No. 339,801.

To all whom it may concern:

Be it known that I, HAROLD JAMES ARNOLD, a subject of the King of Great Britain, residing at 40 Bournville Lane, Stirchley, in the county of Warwick, England, have invented a certain new and useful Improved Spring-Hinge for Use with Swing-Doors or the like; and I do hereby declare the following to be a full, clear, and exact 10 description of the same.

This invention relates to spring hinges such as are used for swing doors and the like, and has for its object to provide a hinge which is acted upon by compression springs in such a manner that its resistance to rotary motion will be very considerable for the first few degrees, after which, up to about 80°, the resistance remains approximately constant, finally increasing very considerably as 90° is approached, the resistance to motion disappearing entirely shortly after a movement of 90°.

A further object of my invention is to provide an arrangement by which after 25 the hinge has been moved from its normal position its return motion will be automatically checked.

A further object of my invention is to provide an arrangement whereby there will 30 be no lost motion between the door or hinge spindle and the mechanism which restrains or controls its motion.

A further object of my invention is to provide means whereby the door can be 35 accurately centered upon the hinge.

Apparatus according to the present invention comprises a hinge spindle having means for securing a door thereto, a cam mounted on or made integral with said 40 spindle, a primary spring pressed sliding plate having one end shaped to cooperate with said cam, a secondary spring pressed sliding plate arranged to exert additional pressure on the primary sliding plate at 45 certain desired angular positions of the hinge spindle, and suitable guides for the sliding plates.

Another feature of my invention is the provision of members pivoted to the primary sliding plate and each having an end bearing on the end of the secondary sliding plate and an end bearing on the end of a casing which contains the apparatus, these pivoted members acting somewhat in 50 the manner of struts between the secondary sliding plate and the casing and also pro-

viding a frictional resistance to return movement of the primary sliding plate which resistance may be at a maximum when the door is wide open and decrease 60 as it closes, thus forming a check to the return movement of the primary sliding plate.

Another feature of my invention is the provision of a hydraulic, pneumatic, or dash pot device to co-act with the primary sliding plate to assist in checking the return swing of the door.

A further feature of my invention is the provision of an arm either integral with the 70 hinge spindle or secured upon a taper square thereon or other means, the free end of this arm being provided with one or more tapped holes whereby the door can be secured thereto by screws or their equivalents, and its 75 angular position in relation to the hinge spindle adjusted as required.

Referring to the drawings:

Figure 1. is a view in side elevation, in section upon the line A—B in Fig. 2. 80

Fig. 2. is a plan view with the top of the casing removed.

Fig. 3. is a plan view with further parts of the casing removed and with the hinge spindle in its central position. 85

Fig. 4. is a similar view to Fig. 3 showing the positions of the parts when the hinge spindle has rotated through about 90°.

Fig. 5. is a view in section on the line C—D in Fig. 1. 90

Fig. 6. is a view illustrating one of the plates removed.

Fig. 7. is a view illustrating the arm made integral with the hinge spindle.

In the construction illustrated the apparatus is contained in a metal casing 1 having the form of a shallow rectangular open topped box. This casing, which is provided with a cover (not shown), is adapted to be embedded in the floor and the hinge 100 spindle 2 is vertically disposed and supported in bearings 3 in the casing. The hinge spindle cam 4, which may be integral with the spindle 2, is shaped somewhat like half an ellipse with a slight depression 5 at the center. 105

The primary sliding plate 6 has one end 7 shaped to cooperate with the cam 4 so that when the hinge spindle 2 is turned at a constant speed the plate 6 is slid along the casing at a speed which is at a maximum at the start and decreases until the full move- 110

ment (about 100°) of the hinge spindle has been made. A compression spring 8 is arranged between the end of the primary sliding plate 6 remote from the cam and the 5 end of the casing 1 so that this spring 8 is tending constantly to keep the hinge spindle 2 in its original position.

The end 7 of the primary sliding plate 6 which co-operates with the cam 4 is shaped to 10 partially inclose the cam 4 so that if the hinge spindle 2 is turned in one direction and then reversed there will be no lost motion between the cam and the engaging end of the primary sliding plate. Thus the door 15 9 will never have free movement independent of the sliding plates.

The bell crank levers 10 are pivoted at 11, 11 to the primary sliding plate 6. As the primary sliding plate is moved along the 20 casing 1 one end 12 of each bell crank lever 10 slides along a channel 13 formed between the end of the casing 1 and the cam like projection 14 upon the bottom of the casing, in contact with the end of the casing 1 and 25 the other end 15 of each bell crank lever 10 is in sliding contact with the one end 16 of the secondary sliding plate 17. This end 16 of the secondary sliding plate 17 is specially shaped as shown in such a way that a pair 30 of compression springs 18, 18 which act upon the secondary sliding plate 17, add to the spring pressure upon the primary sliding plate 6 just at the beginning of the motion of the hinge spindle 2. The end 16 of the 35 secondary sliding plate 17 and the faces of the bell crank levers 10 are however, so shaped that the primary sliding plate 6 is relieved of its additional spring pressure to a great extent after the first few degrees of 40 angular movement of the hinge spindle 2. This relief is effected by means of the bell crank levers 10 which are pivoted at 11 to the primary sliding plate 6, these levers 10 acting in the manner of struts between the 45 end of the casing 1 and the end 16 of the secondary sliding plate 17, which also has the effect of retarding or checking a too rapid closing movement.

The end of the secondary sliding plate 17 50 remote from the cam has two upturned projections 20. These projections are engaged by shoulders 19 upon the end of the primary sliding plate 6, just before a 90° movement of the hinge spindle is reached, thus restoring to the primary sliding plate 6 the additional spring pressure from the pair of compression springs 18 which act upon the secondary sliding plate. The upturned projections 20 upon the secondary sliding plate 55 60 17 are provided with adjusting screw 21 so that the point at which these projections will be engaged by the primary sliding plate 6 can be altered as required.

The three compression springs 8, 18, 18 are each provided with a screw adjustment

at 22 whereby the pressure they exert upon the sliding plates can be altered as desired.

The primary sliding plate 6 may have attached to it a hydraulic, pneumatic, or dash pot device such as 23 to assist checking the 70 return movement of the swing door. This device may be of any usual construction comprising a plunger working in a cylinder. The plunger may be held stationary by a pin 24 attached to the casing 1 of the apparatus, while the cylinder 25 is attached to the primary sliding plate. 75

The hinge spindle 2 is provided with an arm 26 either made integral therewith or fixed upon a taper square 27 or in any other 80 manner. This arm 26 is provided with two tapped holes 27 at its free end. The under side of the door 9 is recessed at 28 to fit over this arm 26 and metal plates 29 are provided upon the door through which, at each side, 85 are screws 30 which enter the tapped holes 27 in the arm 26 upon the hinge spindle 2. By tightening one and slackening the other screw 30 the door can be accurately centered upon the hinge and its angular position 90 thereon adjusted.

Fig. 6 illustrates one of the metal plates 29 and the holes 31 through which the adjusting screws pass to the arm 26, while Fig. 7 illustrates the arm 26 made integral 95 with the hinge spindle 2.

The holes in the metal plates 29 upon the door may take the form of slots 31 extending to the edges of the plates 29 to facilitate removal of the door 9. Screws having a 100 spherical or convex shoulder under the head may be employed and those parts of the plates with which these shoulders come into contact may be correspondingly shaped so as to allow a small angular adjustment of the 105 screws. This arrangement enables a standard size of fitment to be applied to doors of varying widths and dispenses with the use of a shoe beneath the door.

Screws may also be employed having an 110 annular groove or recess under the head into which fit corresponding lugs on the metal plates 29 for the purpose of preventing any tendency the screws may have of becoming detached through the swinging of the doors. 115

In operation assuming that the door 9 is in the closed position, all three compression springs 8, 18, 18 will be acting to keep it in this position. When the door is moved, for the first few degrees of movement it is necessary to compress all three of the compression springs. When the door has been moved a few degrees, a further movement necessitates the continued compression of the primary sliding plate spring 8 but 120 only very slight further compression of the secondary sliding plate springs 18. At this point the bell crank levers 10 which are pivoted at 11 to the primary sliding plate 6 begin to act as struts, in the manner herein- 125 130

before described, so that if the door 9 is now released it will return to its original position under the influence of the spring pressure from the primary sliding plate 6 only, and this movement will be checked by the friction of the bell crank levers 10 and by the dash pot or like device 23 if same is provided. As the opening of the door approaches 90° the shoulders 19 upon the primary sliding plate 6 will come into contact with the projections 20 upon the secondary sliding plate 17 and will restore to the primary sliding plate 6 the full pressure of the three springs 8, 18, 18. If the movement is continued beyond 90° the cam 4 will reach a dead center position in which it acts as a simple strut between the end of the primary sliding plate 6 and the casing 1 and the door 9 will consequently remain open until the cam is moved from this position. When the cam 4 is acting as a strut the pressure from the plate 6 may be transmitted to the casing 1 through the hinge spindle bearings 3, or one end of the cam 4 may make contact with the end of the casing.

The adjustment provided will make springs of one strength suitable for various sizes of doors.

What I claim then is:—

1. A spring hinge for swing doors comprising a hinge spindle having means for securing a door thereto, a cam arranged in operative connection with said spindle, a primary spring pressed sliding plate having one end shaped to coöperate with said cam, a secondary spring pressed sliding plate mounted in lost motion relation to said primary sliding plate, whereby said secondary sliding plate exerts additional pressure upon the primary sliding plate at certain angular positions of the hinge spindle, and guides for said sliding plates.

2. A spring hinge for swing doors comprising a casing containing a hinge spindle having means for securing a door thereto, a cam arranged in operative connection with said spindle, a primary spring pressed sliding plate having one end shaped to coöperate with said cam, a secondary spring pressed sliding plate mounted in lost motion relation to said primary sliding plate, whereby said secondary sliding plate exerts additional pressure upon the primary sliding plate at certain angular positions of the hinge spindle, a pair of levers pivoted to the primary sliding plate, each having one end bearing on the end of the casing and its other end bearing on the end of the secondary sliding plate, said levers acting as struts between the secondary sliding plate and the casing and also providing a frictional resistance to return movement of the primary sliding plate, and guides for said sliding plates.

3. A spring hinge for swing doors com-

prising a hinge spindle having means for securing a door thereto, a cam arranged in operative connection with said spindle, a primary spring pressed sliding plate having one end shaped to coöperate with said cam, 70 a fluid pressure device associated with said primary sliding plate to assist in checking the return swing, a secondary spring pressed sliding plate mounted in lost motion relation to said primary sliding plate, whereby said secondary sliding plate exerts additional pressure upon the primary sliding plate at certain angular positions of the hinge spindle, and guides for said sliding plates.

4. A spring hinge for swing doors comprising a casing containing a hinge spindle having means for securing a door thereto, a cam arranged in operative connection with said spindle, a primary spring pressed sliding plate having one end shaped to coöperate with said cam, a fluid pressure device associated with said primary sliding plate to assist in checking the return swing, a secondary spring pressed sliding plate mounted in lost motion relation to said primary sliding plate, whereby said secondary sliding plate exerts additional pressure upon the primary sliding plate at certain angular positions of the hinge spindle, a pair of levers pivoted to the primary sliding plate, each having one end bearing on the end of the casing and its other end bearing on the end of the secondary sliding plate, said levers acting as struts between the secondary sliding plate and the casing and also providing a frictional resistance to return movement of the primary sliding plate, and guides for said sliding plates.

5. A spring hinge for swing doors comprising a hinge spindle having means for securing a door thereto, a cam arranged in operative connection with said spindle, a primary spring pressed sliding plate having one end shaped to coöperate with said cam, said end being recessed to partially inclose the cam so as to provide surfaces upon which the cam can operate during movement of the plate in either direction and so avoid lost motion between the cam and the plate, a secondary spring pressed sliding plate mounted in lost motion relation to said primary sliding plate, whereby said secondary sliding plate exerts additional pressure upon the primary sliding plate at certain angular positions of the hinge spindle, and guides for said sliding plates.

6. A spring hinge for swing doors comprising a casing containing a hinge spindle having means for securing a door thereto, a cam arranged in operative connection with said spindle, a primary spring pressed sliding plate having one end shaped to coöperate with said cam, said end being recessed to partially inclose the cam so as to provide surfaces upon which the cam can oper-

ate during movement of the plate in either direction and so avoid lost motion between the cam and the plate, a secondary spring pressed sliding plate mounted in lost motion relation to said primary sliding plate, whereby said secondary sliding plate exerts additional pressure upon the primary sliding plate at certain angular positions of the hinge spindle, a pair of levers pivoted to 5 the primary sliding plate, each having one end bearing on the end of the casing and its other end bearing on the end of the secondary sliding plate, said levers acting as struts between the secondary sliding plate 10 and the casing and also providing a frictional resistance to return movement of the primary sliding plate, and guides for said sliding plates.

7. A spring hinge for swing doors comprising a hinge spindle having means for securing a door thereto, a cam arranged in operative connection with said spindle, a primary spring pressed sliding plate having one end shaped to coöperate with said cam, 20 said end being recessed to partially inclose the cam so as to provide surfaces upon which the cam can operate during movement of the plate in either direction and so avoid lost motion between the cam and the plate, 25 a fluid pressure device associated with said primary sliding plate to assist in checking the return swing, a secondary spring pressed sliding plate mounted in lost motion relation to said primary sliding plate, whereby said 30 secondary sliding plate exerts additional pressure upon the primary sliding plate at certain angular positions of the hinge spindle, and guides for said sliding plates.

8. A spring hinge for swing doors comprising a casing containing a hinge spindle having means for securing a door thereto, a cam arranged in operative connection with said spindle, a primary spring pressed slid-

ing plate having one end shaped to coöperate with said cam, said end being recessed 45 to partially inclose the cam so as to provide surfaces upon which the cam can operate during movement of the plate in either direction and so avoid lost motion between the cam and the plate, a fluid pressure device associated with said primary sliding plate to assist in checking the return swing, a secondary spring pressed sliding plate mounted in lost motion relation to said primary sliding plate, whereby said secondary sliding plate exerts additional pressure upon the primary sliding plate at certain angular positions of the hinge spindle, a pair of levers pivoted to the primary sliding plate, each having one end bearing on 50 the end of the casing and its other end bearing on the end of the secondary sliding plate, said levers acting as struts between the secondary sliding plate and the casing and also providing a frictional resistance 55 to return movement of the primary sliding plate, and guides for said sliding plates.

9. A spring hinge for swing doors comprising a hinge spindle, spring means operating in opposition to angular displacement 70 of said hinge spindle, and an arm mounted in driving engagement with said spindle, two separate side plates for attachment to the door, slots in said side plates extending to the edges thereof, said arm being provided with tapped holes in which are oppositely projecting screws whereby the door carrying the side plates can be placed in position without removing the screws and secured to the arm by the screws and its 75 angular position in relation to the hinge spindle adjusted.

In testimony whereof I affix my signature in presence of two witnesses.

HAROLD JAMES ARNOLD.
